UNITED STATES PATENT OFFICE.

WALLACE P. ANDRICK, OF JAMAICA, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

1,333,596.

Specification of Letters Patent. Patented Mar. 16, 1920.

Application filed September 25, 1917. Serial No. 193,112.

To all whom it may concern:

Be it known that I, WALLACE P. ANDRICK, a citizen of the United States, residing at Jamaica, Long Island, in the county of 5 Queens and State of New York, have invented certain new and useful Improvements in Telephone Systems, of which the following is a full, clear, concise, and exact description.

10 This invention relates to telephone systems, and more particularly to intercommunicating telephone systems provided with a trunk circuit extending to a central office and multipled to each of the intercommunicating stations comprising the system.

15 The object of this invention is to provide an improved holding means for the trunk circuit by means of which the trunk circuit may be held while the original answering 20 station is communicating with another station of the system.

25 In accordance with this invention there is provided a bridge for holding the trunk circuit, which may be substituted for the answering telephone set, such substitution being controlled by a differential relay, the energization and deenergization of which is controlled by a local circuit relay and a relay in circuit with the trunk.

30 For a more complete understanding of this invention reference should be had to the following description considered in connection with the accompanying drawing.

35 In the drawing there is shown a trunk circuit comprising conductors 5 and 6, which extends to a central office, not shown. This trunk circuit is multipled to the various stations comprising the system, only two of which—A and B—are shown in the drawing. 40 Each of the stations of the system is provided with the usual telephone set, a trunk answering key T for connecting the telephone set with the trunk circuit, a local answering key L for connecting the telephone set with conductors of the intercommunicating system individual to the particular station, and with the usual keys (2 and 45 3 being shown at station A, and 1 and 3 at station B) which are individual to other 50 stations of the system and which are employed for connecting the telephone set at a calling station with the conductors individual to any called station of the system. Each of the keys is of the locking type, which

when depressed is locked in depressed position by a spring pressed latch plate 16. If a key is locked in depressed position, when a second key is depressed the first key will thereby be released and restored to normal position. Each station is provided with a 60 ringing key R, of the non-locking type, which is employed in signaling between the various stations, there being at each station a signaling device or bell 17 which responds to the depression of the ringing or signaling 65 key R when the proper individual key is in depressed position. Associated with the trunk circuit is a holding bridge 7, composed of a non-inductive resistance which may be substituted for any one of the telephone sets. A differential relay 8 controls this holding bridge 7, and the energization and deenergization of the differential relay 8 is controlled by a local circuit relay 9 and a relay 10 in the trunk circuit. A holding 70 key H, of the non-locking type, located at station A, coöperates with the relay 10 to cause the energization of differential relay 8. While station A is the only one shown equipped with a holding key, still the leads 80 controlled by this key may be multipled to as many stations as desired, and similar holding keys provided thereat. The trunk answering keys T provided at the various stations coöperate with the relays 9 and 10 85 to cause the deenergization of the differential relay 8 to remove the holding bridge 7 from the trunk circuit.

Referring now to the operation of the system shown in the drawings, it will be 90 assumed that the operator at the central office (not shown) has made connection between the cord circuit thereat and the central office end of the trunk circuit, and has projected ringing current out over the trunk 95 circuit to cause the operation of call bell 15, which in the system illustrated in the drawing is shown associated with station A of the intercommunicating system. This station A therefore serves as the answering station 100 of the intercommunicating system, so far as incoming calls over the trunk circuit are concerned. The attendant at station A, in response to the operation of the call bell 15, depresses the trunk answering button T and 105 removes the receiver from the switchhook. Upon the depression of the trunk answering key T at station A and the removal of the

receiver thereat, relay 10 is operated by current furnished from the central office battery over the trunk circuit. If the attendant at station A wishes to transfer the call to station B, the holding key H is momentarily actuated and key 2, individual to station B, is then depressed. The depression of the key 2 releases the trunk answering key T. The momentary depression of the holding key H causes the energization of the differential relay 8 over a circuit from battery through the alternate contact of relay 10, contact of holding key H, and the left-hand winding of differential relay 8 to ground. 10 The differential relay 8, in being energized, attracts its armatures, thereby establishing a locking circuit for itself from battery through its middle alternate contact and left-hand winding to ground. The attraction 15 of the right-hand armature of relay 8 connects the holding bridge 7 across the conductors 5 and 6 of the trunk circuit, so that this bridge 7 remains substituted for the telephone set of station A after the trunk 20 answering key T of station A is restored to normal position by the depression of the individual key 2. The restoration of the trunk answering key T to normal position, following the depression of the individual 25 key 2, opens the circuit of relay 10, which thereupon releases. Relay 9 is thereby actuated over a circuit from battery through the normal contact of relay 10, left-hand alternate contact of differential relay 8 and the 30 winding of relay 9 to ground. Relay 9, in operating, completes a locking circuit for itself from battery through the middle alternate contact of differential relay 8, left-hand alternate contact of relay 9 and the winding 35 thereof to ground. The closure of the right-contact of relay 9 prepares a circuit for the right-hand winding of differential relay 8. The attendant at station A after actuating the individual key 2 then depresses the ringing 40 key R, thereby causing the operation of the signaling device 17 at station B over a circuit from battery through this signaling device 17, contact 18 controlled by the switchhook of the telephone set, conductors 19 and 45 20, contact 21 of individual key 2 and the alternate contact of ringing key R to ground. The party at station B, in response to the actuation of the signaling device 17, depresses the local answering key L and removes 50 the receiver from the switchhook, thereby connecting the telephone set of station B in circuit with the telephone set of station A. Talking battery for the telephone set at station B is furnished from the talking battery TB over conductor 25, through the left-hand winding of retardation coil 26, contact 27 of the local answering key L, the transmitter, switchhook contact and the winding of the induction coil of the telephone set at station B, contact 28 of the local 55

answering key L, the right-hand winding of retardation coil 26, and conductor 29 back to the talking battery TB. Talking battery for the telephone set at station A is also furnished through the windings of retardation coil 26, the circuit being traced from the battery TB through conductor 25, left-hand winding of retardation coil 26, conductor 30, contact 31 controlled by the switchhook of the telephone set at station B, conductors 19 and 20, contact 21 of key 2, normal contact of ringing key R at station A, the transmitter, the switchhook contact and winding of the induction coil of the telephone set at station A, contact 32 of key 2, 80 conductors 33 and 34, the right-hand winding of retardation coil 26, and conductor 29 back to the battery TB. After the attendant at station A has advised the party at station B that the incoming call is for station B, 85 the attendant restores the receiver to the switchhook, and the party at station B depresses the trunk answering button T, thereby restoring the local answering key L to normal position. The restoration of the local answering key L to normal position disconnects the telephone set of station B from station A, and the depression of the trunk answering key T connects this telephone set of station B with the trunk circuit. 90 Upon the telephone set of station B being connected to the trunk circuit, a circuit including relay 10 is established, whereupon this relay attracts its armatures. The attraction of the armature of relay 10 completes a circuit for the right-hand winding of differential relay 8 which may be traced from battery through the alternate contact of relay 10, right-hand contact of relay 9 and the right-hand winding of differential 100 relay 8 to ground. Current now traverses both windings of the differential relay 8, and since this relay is differentially wound, the magnetization produced by one winding neutralizes that produced by the other, and the relay releases its armatures, whereupon the holding bridge 7 is removed from the trunk circuit and relay 9 is released. Upon the conclusion of the conversation over the trunk circuit the party at station B restores the receiver to the switchhook, whereupon relay 10 releases its armature and the usual supervisory relay of the cord circuit at the central office (not shown) is released to cause the lighting of the usual supervisory disconnect 115 lamp (not shown). 120

From the above description it will be apparent that this invention provides a system in which there is no chance that the trunk circuit will be momentarily opened while transferring an incoming call over the trunk circuit to another station. In cord circuits equipped for flashing recall, for example, in the manner set forth in the Smythe Patent No. 758,116, the momentary opening of the 130

trunk circuit would cause the supervisory lamp of the cord circuit to glow intermittently to indicate a recall signal, thereby causing the operator to come in on the connection when in fact the operator was not desired at all. The present system, by providing a non-locking holding key and controlling apparatus in the form of the relays shown and described, which function before the telephone set is disconnected from the trunk circuit, insures that the trunk circuit will not be opened while transferring a call, and in this manner the possibility of causing the premature actuation of the recall apparatus at the central office is avoided.

What is claimed is:

1. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, switching means including a differential relay controlling such substitution, a relay in the trunk circuit, an energizing circuit for the differential relay completed through a contact of the trunk relay, a local circuit relay, and a releasing circuit for the differential relay completed through contacts of the trunk and local circuit relays when energized.

2. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, a key, a relay in the trunk circuit, a second relay energized upon the actuation of the key while the trunk relay is energized to connect the bridge across the trunk circuit, a third relay energized upon the subsequent deenergization of the trunk relay when the telephone set is disconnected from the trunk circuit, switching means for reconnecting the telephone set to the trunk circuit, thereby causing the energization of the trunk relay, and a disabling circuit for the second relay including contacts of the trunk and third relays established upon such second energization of the trunk relay to cause the deenergization of the second relay.

3. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, a relay in the trunk circuit energized upon connection of a telephone set therewith, a key, a second relay when energized connecting the bridge across the trunk circuit, an energizing circuit for the second relay completed upon the actuation of the key while the trunk relay is energized, and

a disabling circuit for the second relay partially established upon the deenergization of the trunk relay following the disconnection of the telephone set from the trunk circuit, and completely established upon the subsequent energization of the trunk relay thereby to cause the deenergization of the second relay.

4. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, a relay in the trunk circuit energized upon connection of a telephone set therewith, a key, a second relay having an energizing and a neutralizing winding and adapted when energized to connect the bridge across the trunk circuit, a circuit including the energizing winding completed upon the actuation of the key while the trunk relay is energized, a third relay energized upon the subsequent deenergization of the trunk relay following the disconnection of the telephone set from the trunk circuit, switching mechanism for reconnecting a telephone set with the trunk circuit, and a circuit including the neutralizing winding of the second relay completed upon the energization of the trunk relay following the reconnection of the telephone set to the trunk circuit whereby the second relay is deenergized.

5. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, switching means including a relay controlling such substitution, means including a relay in the trunk circuit for causing the energization of the bridge connecting relay, and a local circuit relay when energized coöperating with the trunk relay when subsequently energized to cause the deenergization of the bridge connecting relay.

6. In a telephone exchange system, in combination, a plurality of subscribers' stations, a trunk circuit multiplied to the stations, a telephone set at each station adapted to be connected with the trunk circuit, a bridge for holding the trunk circuit in substitution of the telephone set, a relay in the trunk circuit energized upon the connection of the telephone set thereto, a key, a relay energized upon the operation of the key while the first relay is energized to connect the bridge across the trunk circuit, a locking circuit for the second relay established upon the energization thereof, and a third relay operated upon the subsequent release of the first relay and coöperating

with the first relay when subsequently energized to cause the release of the second relay.

7. In a telephone system, in combination, a plurality of subscribers' stations, a trunk circuit multiplied to the stations, a telephone set at each station adapted to be connected with the trunk circuit, a bridge for holding the trunk circuit in substitution of the telephone set, a relay in the trunk circuit energized upon the connection of the telephone set thereto, a key, a second relay controlled by said key while the first relay is energized to connect the bridge across the trunk circuit, a third relay operating upon the de-energization of the first relay, and a disabling circuit for the second relay including contacts of the first and third relays established upon the reenergization of the first relay and the energization of the third relay to cause the release of the second relay.

8. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, a relay when energized connecting the bridge across the trunk circuit, a relay in the trunk circuit energized upon the connection of the telephone set with the trunk circuit, a switch coöperating with the energized trunk relay to cause the energization of the bridge-connecting relay, and means independent of the switch actuated subsequent to the connection of the bridge with the trunk circuit to disconnect the telephone set therefrom.

40. 9. In a telephone system, in combination, a plurality of subscribers' stations, a trunk circuit multiplied to the stations, a telephone set at each station adapted to be connected with the trunk circuit, a bridge for holding the trunk circuit in substitution of a telephone set, a relay when energized connecting the bridge across the trunk circuit, a relay in the trunk circuit energized upon the connection of the telephone set with the trunk circuit, a switch coöperating with the energized trunk relay to cause the energization of the bridge connecting relay, means independent of the switch actuated subsequent to the connection of the bridge with the trunk circuit to disconnect the telephone set therefrom, and a disabling circuit for the bridge-connecting relay established upon the subsequent energization of the trunk relay by the connection of the telephone set with the trunk circuit whereby the bridge is disconnected therefrom.

10. In a telephone system, in combination, a plurality of subscribers' stations, a trunk circuit multiplied to the stations, a telephone set at each station, a switch at each station

controlling the connection of the telephone set thereat with the trunk circuit, a bridge for holding the trunk circuit in substitution for a telephone set, a relay for connecting the bridge across the trunk circuit, a relay in the trunk circuit energized upon the connection of the telephone set therewith, a switch momentarily actuated and coöperating with the energized trunk relay to cause the energization of the bridge-connecting relay, and means independent of the last-mentioned switch actuated subsequent to the connection of the bridge with the trunk circuit to disconnect the telephone set therefrom.

11. In a telephone system, in combination, a plurality of subscribers' stations, a trunk circuit multiplied to the stations, a telephone set at each station, a switch at each station controlling the connection of the telephone set thereat with the trunk circuit, a bridge for holding the trunk circuit in substitution for a telephone set, a relay for connecting the bridge across the trunk circuit, a relay in the trunk circuit energized upon the connection of the telephone set therewith, a switch momentarily actuated and coöperating with the energized trunk relay to cause the energization of the bridge-connecting relay, means independent of the last-mentioned switch actuated subsequent to the connection of the bridge with the trunk circuit to disconnect the telephone set therefrom, and a disabling circuit for the bridge-connecting relay established upon the subsequent energization of the trunk relay due to the connection of the telephone set with the trunk circuit whereby the bridge is disconnected therefrom.

12. In a telephone system, in combination, a plurality of subscribers' stations, a trunk circuit multiplied to the stations, a telephone set at each station adapted to be connected with the trunk circuit, a locking key at each station controlling the connection of the telephone set thereat with the trunk circuit, a bridge for holding the trunk circuit in substitution of a telephone set, a relay when energized connecting the bridge across the trunk circuit, a relay in the trunk circuit energized while a telephone set is connected therewith, a non-locking key coöperating when actuated with the energized trunk relay to cause the energization of the bridge-connecting relay, a locking circuit for the bridge-connecting relay established upon its energization, and means actuated subsequent to the connection of the bridge with the trunk circuit to disconnect the telephone set therefrom.

13. In a telephone system, in combination, a plurality of subscribers' stations, a trunk circuit multiplied to the stations, a telephone set at each station adapted to be connected with the trunk circuit, a locking key

at each station controlling the connection of the telephone set thereat with the trunk circuit, a bridge for holding the trunk circuit in substitution of a telephone set, a relay 5 when energized connecting the bridge across the trunk circuit, a relay in the trunk circuit energized while a telephone set is connected therewith, a non-locking key coöperating when actuated with the energized trunk relay to cause the energization of the bridge-connecting relay, a locking circuit for the bridge-connecting relay established upon its energization, means actuated subsequent to the connection of the bridge with the trunk 10 circuit to disconnect the telephone set therefrom, and a disabling circuit for the bridge-connecting relay established upon the subsequent energization of the trunk relay due to the connection of the telephone set with the trunk circuit whereby the bridge is disconnected therefrom.

14. In a telephone system, in combination, a plurality of subscribers' stations, a trunk

circuit multiplied to the stations, a telephone set at each station, a locking key at 25 each station controlling the connection of the telephone set thereat with the trunk circuit, a bridge for holding the trunk circuit in substitution of a telephone set, a relay in the trunk circuit, a relay for connecting the 30 bridge across the trunk circuit, a non-locking key, an energizing circuit for the bridge-connecting relay completed upon the momentary actuation of the non-locking key when the trunk relay is energized, a locking circuit for the bridge-connecting relay established upon the energization thereof, and a disabling circuit for the bridge-connecting relay established upon the subsequent energization of the trunk relay due to 35 the actuation of one of the locking keys.

In witness whereof I hereunto subscribe my name this 19th day of September, A. D. 1917.

WALLACE P. ANDRICK.
